tension present due to its mass and high temperature and to produce sharp irregularities in the tension surface at the points 18 where it separates from the side wall 20 of the tip 14.

The tension pattern thus produced will tend to cause the cracks or checks (not shown) previously mentioned aided by the poor strength of glass in tension. The cracks or checks will often develop slowly, due to residual tension and the fatigue characteristic of glass, sometimes penetrating the side wall 20 of the tip 14 destroying the vacuum tight seal. In most cases, the checks do not penetrate the side wall 20, but so weaken it that the slightest force on the tip 14 normal to its axis will cause it to crack or break off completely. It has been found that between 25% and 40% of the electron tubes tipped off according to the prior art will have or will develop checked tips.

Figures 2 and 3 depict elements according to this invention for tipping off the glass exhaust tubulation of an electron tube 10. Referring to Figure 2, the glass tubulation 22 of the electron tube 10 is inserted into a vacuum port 24 whereby the tube 10 may be evacuated. Heat is applied to the exhaust tubulation 22 at a point near the envelope 12 of the tube 10 as by the direction of gas flames 26 against the tubulation 22. The electron tube 10 should be supported by some means (tongs 28 for example) while the flames 26 are heating the tubulation 22 due to the fact that the tubulation 22 will be softened by the heat and would allow the tube 10 to fall if it were not independently supported. When the tubulation 22 has reached the plastic state, opposed cutters 30 (two for example) are brought into contact with the heated portion of the tubulation 22.

Referring to Figure 3, the cutters 30 collapse the tubulation 22 causing it to fuse shut, and sever it in two. It will be seen that the cutting edges 32 of the opposed cutters 30 have a configuration (semi-circular, according to the embodiment shown) for the purpose of imparting a desired shape to the tip 34 of the tubulation 22. As in this embodiment of the invention, the cutting edges 32 may be provided by forming depressions 36 and tapers 38 in the opposed ends of the cutters 30. The depressions 36 comprise a mold which aids the cutting edges 32 in imparting the desired shape to the tip 34 and thus the cutters 30 are oriented with respect to the electron tube 10 so that the depressions 36 open toward the electron tube 10. The tapers 38 impart a sharpness or knife-like characteristic to the cutting edges 32 to facilitate the accomplishment of the tip-off with a minimum of unevenness and irregularity in the end surface 42 of the tip 34.

As soon as the tubulation 22 is severed, the tube 10 may be removed from the tip-off position without further heating. Due to the fact that the cutters 30 are unheated and may be of heat conducting material, such as metal for example, the tip 34 is cooled before any appreciable amount of glass may be rendered molten and forced inwardly of the tip 34 by atmospheric pressure.

Referring to Figure 4 which shows an electron tube 10 tipped off according to this invention, it will be seen that there is no ball of glass within the tip 34. Furthermore, it will be seen that the tip 34 has a hemispherical or smoothly contoured, vaulted inner surface 40. It has been found that the vaulted inner surface 40 provides much greater tip strength due to the inherent stress distribution characteristic of such a surface in addition to the fact that the uneven strain patterns produced by the ball 16 of glass shown in Figure 1 are not present in the tip 34 shown in Figure 4. A further advantage of a tip 34 produced according to this invention is that it is less likely to be injurious to human hands due to the rounded or dome-shaped end surface 42 of the tip 34 as compared to the sharp spire-like end surface 42 of the tip 14 produced according to the prior art.

The cutters 30 used according to this invention may take a variety of shapes and may be composed of any

one of a variety of materials. I prefer to use metallic cutters due to the heat conducting properties of metal in addition to the inherent strength and ruggedness of most metals. For example, the tungsten and tantalum carbides when bonded with cobalt or other metal of the iron group display good heat conducting properties, are capable of being formed to the shapes desired, and yet have sufficient ruggedness to withstand extensive use at elevated temperatures.

The shape of the cutters 30 is determined by the desired contour of the inner surface 40 of the tip 34. I prefer a tip 34 having a hemispherically vaulted inner surface 40 due to the structural strength displayed by such contour. For this reason, I have used cutters 30 having concave depressions 36 formed therein which will comprise a hemispheric mold for the tip 34 when the cutters are closed. However, such cutters 30 are somewhat difficult to fabricate. In addition, it has been found that softened glass is not exactly molded by bringing into contact therewith metallic molds. This is believed to be due to the cooling effect of the molds which tends to cause a more viscous skin or surface on the glass at the area of contact. Referring to Figure 3, it will be seen that the tip 34 produced is not in molded contact with the cutters 30. However, it has been found that by giving the cutters 30 the proper configuration, a desired contour may be produced in the inner surface 40 of the tip 34 although such contour may not be the molded image of the cutters.

For example, it has been found that trough shaped cutters comprising two co-axial, hollow half-cylinders, one having an outer surface matching the inner surface of the other so that one may telescope within the other, will produce a tip having an inner surface 40 that is substantially hemispheric. Referring to Figures 5 and 6, a tipping tool having hollow half-cylindrical cutters 44, 46 is shown in its closed position. The cutters 44, 46 comprise a first hollow half cylinder 44 having an inner surface 48 of larger radius than that of the exhaust tubulation to be tipped off (twice as large, for example). A second hollow half-cylinder 46 co-axial with the first hollow half cylinder 44 having an inner surface 50 of approximately equal radius to the radius of the outer surface 52 of the first hollow half cylinder 44 is shown in engagement with the first half cylinder 44 such that an end of the first half cylinder 44 is inserted into an end of the second half cylinder 46. The opposed ends of the half cylinders 44, 46 which are brought into engagement have oppositely beveled edges 54 to provide each cutter 44, 46 with a knife like cutting action. That is, the inner surface 48 of the first half cylinder 44 is shorter than its outer surface 52 whereas the outer surface 56 of the second half cylinder 46 is shorter than its inner surface 50. The outer surface 52 of the first half cylinder 44 and the inner surface 50 of the second half cylinder 46 are brought into sliding contact with each other thus providing positive cutting action.

The cutters are oriented with respect to the electron tube 10 and exhaust tubulation (not shown in Figures 5 or 6) so that their concave inner surfaces 48 and 50 are presented toward the electron tube and their axis is perpendicular to the axis of the exhaust tubulation. Thus, the semi-circular cutting edges 54 of the cutters 44, 46, will extend transversely across the exhaust tubulation 22 and will arch away from the electron tube 10 to impart curvature to the tip 34. In addition, when the cutters 44, 46 are brought into contact with the tubulation at the beginning of their cutting action, they will tend to deform portions of the tip adjacent the cutters but not in contact therewith. This deformation will constitute a curvature of the side walls of the tip 34 as they are compressed, which when combined with the curvature heretofore mentioned will impart to the inner surface 40 of the tip 34 a vaulted or substantially hemispheric contour.

The telescoping or overlapping of the half cylindrical cutters 44, 46 provides a positive cutting action which is not easily obtained with hemispheric mold type of cutters 30. It will be apparent that the quarter spherical depression 36 of the cutters 30 shown in Figures 2 and 3 could not be adapted to telescope or overlap to any useful extent without imparting to the cutters 30 some rotary motion in addition to the rectilinear motion 58 as indicated. The telescoping action of the half cylindrical cutters 44, 46 insures a clean cut-off of the tubulation without the production of a fin or ridge of compressed glass on the end surface 42 of the tip 34 at the point of contact of the cutters 44, 46.

Referring to Figures 7 and 8, additional advantages may be obtained by providing the half cylindrical cutters 44, 46 with re-entrant cutting edges 60. According to the embodiment shown, the opposed ends of the half cylindrical cutters 44, 46 are each shortened intermediate their side edges 62 in planes at an angle to their axes, forming an arcuate and re-entrant cutting edge therein. When these cutters 44, 46 are advanced toward each other, the portions of their cutting edges 60 adjacent their side edges 62 will come into engagement first and their cutting edges 60 will form an aperture which will constrict from all sides as the advance of the cutters 44, 46 is continued. This cutting action will impart additional curvature to the tip 34 produced which will more nearly approximate the desired hemispheric shape.

A lip or flange 64 may be provided on each side edge 62 of the larger half cylinder 46 adjacent the cutting edge 60 thereof to contact the side edges 62 of the smaller half cylinder and insure the close engagement of the two cutters 44, 46.

The means for bringing cutters, according to this invention, into engagement may also take a variety of forms. In a successfully tested device, the hemispherical mold type of cutters 30 such as are shown in Figures 2 and 3 having a radius of approximately 2 centimeters, were attached to the jaws 66 of a plier-like device 68 as shown in Figure 9. An electron tube 10 having a glass tubulation 22 of approximately 1.5 centimeters radius was evacuated and a portion of the tubulation 22 heated. The electron tube 10 was supported while the tubulation 22 was heated as by a pair of tongs 28. The pliers 68 having the shaped cutters 30 were then closed on the heated portion of the tubulation 22 to tip-off the tube 10. Tips 34 produced by this method were found to be free of the ball or bubble of glass and the cracks or checks produced thereby and to have a vaulted and substantially hemispheric inner surface 40.

In a special testing device, the tips 34 produced as described according to this invention were found to withstand thirty or more pounds of force applied normally to the axis of the tip whereas tips made according to the prior art could only withstand forces of approximately twenty-five pounds if unchecked and eight pounds if checked.

In addition to the advantage of producing stronger tips, another advantage of this invention is that the tip-off may be made in much less time than was necessary

according to the prior art. This is due to the fact that the heated portion of the glass tubulation does not have to be raised to its melting temperature according to this invention whereas it had to be actually melted in two according to the prior art. This fact has two advantageous aspects, first in that the actual heating time is less and second in that the flames of the tipping torches or other heating means may be made hotter for even greater speed without any adverse effects, whereas if the flames are made hotter in the tipping-off process of the prior art in order to speed up the process, more checked tips will result due to the relatively larger ball of inwardly extending glass produced thereby.

It is apparent that an improved glass tip for an electron tube is herein described. In addition, an improved method of and means for tipping-off the glass tubulation of an electron tube is herein provided which is inherently suited for use with automatic machinery for the fabrication of electron tubes where the tip-off must be made rapidly in order to keep up with other automatic operations.

What is claimed is:

Apparatus for tipping off an evacuated electron tube having a pre-heated glass exhaust tubulation comprising two hollow half-cylindrical cutters, one end of each of said cutters being shortened intermediate the side edges thereof whereby an arcuate and re-entrant cutting edge is provided, one of said cutters having an outer surface and the other of said cutters having an inner surface of substantially equal radius, and means attached to said cutters for positioning said cutters in spaced co-axial relationship, whereby said cutting edges of said cutters are opposed to each other, and for moving said cutters axially toward each other and into engagement, whereby said one of said cutters is inserted into said other of said cutters.
